UNITED STATES PATENT OFFICE.

JOHN E. DUNGAN, OF CANTON, OHIO, ASSIGNOR OF ONE-HALF TO THE THOMAS-PETER COMPANY, OF CANTON, OHIO, A CORPORATION OF OHIO.

FILING DEVICE.

1,205,604.

Specification of Letters Patent. Patented Nov. 21, 1916.

Application filed May 27, 1915. Serial No. 30,841.

To all whom it may concern:

Be it known that I, JOHN E. DUNGAN, a citizen of the United States, residing at Canton, in the county of Stark and State of Ohio, have invented a new and useful Filing Device, of which the following is a specification.

My invention relates to new and useful improvements in filing devices and has more especial reference to a device designed especially for keeping slips or cards containing records, it being understood that it is applicable wherever records of any character are kept.

15 The object of my invention is to provide a filing device provided with means for facilitating the filing of records under different items or headings.

20 A further object is to provide a filing device of this character by the use of which any desired records may be produced almost instantly with very little effort of the operator.

With these objects in view the invention 25 consists in the novel construction and arrangement of parts, hereinafter described, illustrated in the accompanying drawings, and particularly pointed out in the appended claims, it being understood that various 30 changes in the form, proportions, size and minor details of construction may be made within the scope of the appended claims without departing from the spirit or sacrificing any of the advantages of the invention.

35 In the accompanying drawings: Figure 1 is a perspective view of a filing case embodying my improved construction. Fig. 2 is a vertical sectional view through the same. Fig. 3 is a detail perspective view of a portion 40 of the receptacle within which the trays are slidably mounted, showing one of the trays in the open position. Fig. 4 is a section on the line 4-4, Fig. 3. Fig. 5 is a detail perspective view of one of the trays. Fig. 6 is an inverted perspective view of a portion of one of the trays. Fig. 7 is a detail sectional view of a portion of one of the trays showing the same in a closed position. Fig. 8 is a similar view showing the tray in the open position. Fig. 9 is a detail sectional view of the front portion of one of the trays showing the means of connecting the retaining wire thereto.

55 Similar numerals of reference indicate

corresponding parts throughout all the figures of the drawings.

The case or cabinet within which the filing device is contained is composed of spaced metal sheets, the outer sheets being lined with asbestos or similar material and an air space being formed between said asbestos and the inner shell of the casing, thus rendering the cabinet fireproof and preventing records contained therein from becoming 65 damaged by excessive heat. The base comprises the horizontal sheet 1 provided with suitable molding 2 around its edges, the molding along the forward edge being provided with a down-turned flange 3, which 70 extends downwardly against the sheet 1. The sheet 4 forming the rear wall of the cabinet is preferably located perpendicular to the sheet 1, the upper end of said sheet being bent forwardly forming the horizontal 75 top wall 5 which extends downwardly at 6 and is provided with the in-turned portions forming shoulders 7 and 8 connected by the downwardly disposed flange 9. The inner wall of the casing is spaced from the 80 outer wall and comprises the top horizontal wall 10, the forward extremity of which rests upon the shoulder 8, the angular forwardly and downwardly inclined back wall 11 and the angular forwardly and upwardly 85 inclined bottom wall 12, the forward flange 13 of which is vertically disposed and located in juxtaposition to the flange 3 of the front molding of the base. The inner surfaces of the outer walls of the cabinet or 90 casing are lined with sheets 14 of asbestos or similar material and a considerable air space 15 is left between said fireproof lining and the inner walls of the casing.

The receptacle 16 within which the slip 95 holding trays are slidably mounted is placed within the casing or cabinet as shown in Fig. 2, the bottom wall 17 of said receptacle resting upon the inner bottom wall 12 of the cabinet, said wall 17 being provided along 100 its forward extremity with the in-turned flange 18. The top wall 19 of the receptacle is provided at its forward extremity with a similar in-turned flange 20.

The receptacle 16 is provided with a series 105 of vertical partitions 21 arranged in pairs, each of said partitions being provided at spaced intervals with rearwardly inclined grooves 22, said grooves being preferably formed by stamping ribs 23 in the partitions 110

- as best shown in Fig. 4. Adjacent partitions are preferably connected together by means of electrically welding the ribs.
- A plurality of drawers 24 are preferably 5 provided within the slip holding receptacle, said drawers being slidably mounted between the partitions 21 and the lower wall 17, the forward extremity of each drawer resting upon the in-turned flange 18, a substantially 10 U-shaped strip 25 being provided upon the rear extremity of each drawer, said U-shaped member being adapted to slide upon the wall 17 and to contact with the flange 18 limiting the movement of the drawer.
- 15 Each of the slip holding trays 26 is provided along its lateral edges with up-turned substantially vertical flanges 27 and upon its forward edge with the rearwardly inclined flange 28 upon which is preferably 20 mounted a finger piece 29 by which the trays are manipulated. A label holder 30 is also provided upon the forward flange 28 of each of the slip holding trays. A slip retaining wire frame 31 is connected at its extremities 25 to the rear face of the flange 28 and rearwardly disposed therefrom, said wire frame being spaced from the body of the tray 26 and preferably located in a plane parallel thereto.
- 30 One leaf 32 of a butt-hinge is connected in any suitable manner to the rear extremity of each of the trays 26, the other leaf 33 of the hinge being normally located at right angles thereto and provided with a forwardly disposed flange 34. A pintle 35 is 35 passed through the knuckles 36 of the hinge leaves, the extremities of said pintle extending out beyond the knuckles at either side and being slidably located within the grooves 40 22 formed in the partitions 21. Each leaf 33 is provided at its extremities with a pair of rearwardly disposed flanges 37, said flanges being provided along their lower edges with outturned lugs 38, the outer extremities of said lugs being preferably bent back as shown at 39, thus forming lugs of 45 proper thickness to be slidably mounted within the grooves 22 without permitting any lost motion.
- 50 A door is preferably provided upon the forward side of the cabinet for the purpose of covering the slip holding trays when they are not in use and this door is composed of the inner and outer spaced walls 40 and 41, 55 respectively, said walls being connected by suitable top and bottom and side walls 42, said walls 42 being preferably formed as shown in Fig. 1. A lining 43 of asbestos or any other suitable fireproof material is 60 placed upon the inner surface of the wall 41, said lining being spaced as shown from the wall 40.
- When it is desired to refer to slips or place new slips in any of the trays the finger piece 65 29 of any tray desired is grasped and the

tray pulled forward, the forward extremity of the tray sliding upon the strip 45, the pintle 35 and lugs 38 sliding within the grooves 22 formed in the partitions. The normal position of the leaf 33 of the hinge 70 and its forwardly projecting flange 34 is best shown in Figs. 2, 5 and 7. As the tray reaches the limit of its forward movement the pintle 35 will contact with the vertical strips 46 which are provided upon the forward extremities of the partitions 21. The tray may then be lowered into the position shown in Fig. 2 when any slips desired may be removed from or placed beneath the wire frame 31. It will be noticed that at this 80 time the body of the tray will have dropped into a substantially vertical position while the position of the leaf 33 and flange 44 is not changed, thus conveniently permitting slips to be placed within or removed from the tray. When it is desired to return the tray to its normal position, the tray is raised into a substantially horizontal position and pushed back into the cabinet. The flange 34 when the tray is in the normal position, will 85 extend over the inner edges of the slips within the tray, thus preventing the edges from curling up or from being accidentally displaced from the movement of the tray.

As best shown in Fig. 9 the wire retaining frame 31 is preferably secured to the front flange 28 of the tray 26. The extremities of the wire 31 are bent downwardly as at 47 and upwardly as at 48 forming U-shaped portions. The forward flange 28 of the tray is provided with a down-turned portion 49 between which and the front flange 28 the up-turned ends 48 of the wire frame are firmly held.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

I claim:

1. In a device of the character described, a receptacle provided with substantially horizontal grooves in its side walls, a plurality of movable trays slidably mounted within said grooves, means for tilting the trays when the same are moved out of their normal position, hinge members carried upon the rear extremities of said trays provided with overhanging flanges located within the horizontal grooves and projecting beyond the side edges of the tray, said flanges adapted to hold the hinge members against pivotal movement with reference to the grooves, whereby the contents of the trays are re- 130

leased when in a lowered position and clamped when in their normal position.

2. In a device of the character described, a receptacle provided with substantially 5 horizontal grooves in its side walls, a plurality of trays slidably mounted between said side walls, supporting members between said side walls arranged to normally support the forward extremities of said trays; 10 pins carried at the rear extremity of said trays and slidably mounted within said grooves, a hinged member located at the rear extremity of each tray and provided with a forwardly extending flange normally 15 located above and parallel to the tray and ears carried by said hinged members, said ears being located within said grooves.
3. In a device of the character described, a receptacle provided with substantially 20 horizontal grooves in its side walls, a plurality of movable trays suitably supported one above the other within said receptacle, supporting members carried between said side walls and adapted to normally support 25 the forward extremity of each tray, each of said trays being provided with up-turned flanges upon its forward and side edges, a rearwardly disposed retaining frame carried by the forward flange, an upwardly

disposed member hinged at the rear extremity of each tray, a forwardly disposed flange provided upon said hinged member, a pintle arranged to hingedly connect said member to said tray, the extremities of said pintle being slidably mounted within said 30 grooves and ears carried by said hinged member, said ears being slidably mounted within said grooves.

4. In a device of the character described, a receptacle provided with substantially 40 horizontal grooves in its side walls, a plurality of movable trays slidably supported within the receptacle, each of said trays being provided with up-turned flanges upon its forward and side edges, a hinged member 45 connected to the rear extremity of each tray, projections carried by said hinged members and located within said grooves, said trays being adapted to be tilted into a substantially vertical position when the same are 50 moved out of their normal position and a finger piece located at one extremity of the forward up-turned flange, said finger pieces being off-set for the purpose of allowing the trays to be tilted as described.

In testimony that I claim the above, I have hereunto subscribed my name.

JOHN E. DUNGAN.
